(57) **CLAIM**

The ornamental design for a plant light, as shown and described.

DESCRIPTION

FIG. 1 is a perspective view of a plant light showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and

FIG. 8 is a bottom plan view thereof;

FIG. 9 is an enlarged view of partial portion of FIG. 1;

FIG. 10 is an enlarged view of partial portion of FIG. 1; and,

FIG. 11 is an enlarged view of partial portion of FIG. 2.

The dashed or broken lines shown in the drawings depict portions of the plant light in which the design is embodied that form no part of the claimed design.
